UNITED STATES PATENT OFFICE.

CHARLES DANIELSON, OF CANNON FALLS, MINNESOTA.

IRONING-BOARD.

1,073,404.

Specification of Letters Patent. Patented Sept. 16, 1913.

Application filed December 9, 1912. Serial No. 735,683.

To all whom it may concern:

Be it known that I, CHARLES DANIELSON, a citizen of the United States, residing at Cannon Falls, in the county of Goodhue and 5 State of Minnesota, have invented certain new and useful Improvements in Ironing-Boards; and I do hereby declare the following to be a full, clear, and exact description of the invention, such as will enable others 10 skilled in the art to which it appertains to make and use the same.

My invention has for its object to provide an improved ironing board and, to this end, it consists of the novel devices and combinations of devices hereinafter described 15 and defined in the claims.

The invention is illustrated in the accompanying drawings, wherein like characters indicate like parts throughout the several 20 views.

Referring to the drawings: Figure 1 is a side elevation of the improved ironing board supported from the top of a kitchen table, some parts being broken away; Fig. 2 is a 25 plan view of the parts shown in Fig. 1, some parts being broken away; Fig. 3 is a rear end elevation of the parts shown in Figs. 1 and 2; and Fig. 4 is a perspective view of the rear end portion of the ironing board.

30 The numerals 1 and 2 indicate, respectively, a main ironing board and an auxiliary ironing board. Secured to the front and rear end portions, respectively, of the main ironing board 1 are a pair of short 35 legs 3 and a single short leg 4. The legs 3 are laterally spaced apart and secured to the outer edge portion of the main ironing board 1 by a pair of hinges 5, arranged to permit the said legs 3 to be folded inward toward 40 each other, into flat engagement with the main ironing board 1. The short leg 4 is secured to the main ironing board 1 by a hinge 6, arranged to permit said leg 4 to be folded toward the legs 3 longitudinally 45 of the main ironing board 1. When in operative positions, the legs 3 and 4 extend obliquely downward, toward the transverse center of the main ironing board 1. At their free ends, the legs 3 and 4 are formed, respectively, with notches 7 and 8, adapted to 50 embrace opposite edges of the top of a kitchen table indicated, as an entirety, by the character Y. Obviously, the weight of the main ironing board 1 holds the notched 55 ends of the legs 3 and 4 engaged with the opposite edges of the top of the table Y and,

under increased pressure on the ironing board 1, the leg 4 tends to fold inward toward the main ironing board 1, and thereby draws the opposing notched ends 7 and 8 60 of the legs 3 and 4 into tighter engagement with the top of the table Y.

To apply a skirt to the main ironing board 1, the front end thereof is elevated a distance sufficient to carry the notched end 8 65 of the leg 4 out of contact with the top of the table Y. In this position of the parts, the skirt may be slipped over the elevated end of the main ironing board 1. During the application of the skirt to the ironing 70 board 1, the leg 4 will fold, when engaged by the skirt, into close engagement with the main ironing board 1, thereby permitting the skirt to freely slip thereover. After the skirt is past the leg 4, said leg 4 will drop, 75 under the action of gravity, into an operative position, and with the lowering of the elevated end of the main ironing board, its notched end 8 will again embrace the adjacent edge of the top of the table Y. A rest 80 block 9 is provided with a pair of laterally spaced depending and rearwardly converging side flanges 10, rigidly secured to the top rear end portion of the main ironing board 1. The top of the rest block 9 is cov- 85 ered with a non-combustible heat insulating material 11, such as asbestos, and affords a suitable sad iron support.

To prevent a sad iron from slipping off from the rest block 9, when one end of the 90 ironing board 1 is raised for the purpose of removing a garment therefrom, a pair of spaced retaining flanges 9^a is rigidly secured to the top outer side edges of the rest block 9. As shown in Fig. 4, the forward 95 ends of these retaining flanges 9^a are outwardly curved, to form a side entrance passage therebetween and their rear ends terminate in reversely formed inturned stop lugs against which the heel of a single pointed iron rests. The opposing faces of the stop lugs of the retaining flanges 9^a are reversely beveled, to receive the pointed end of a sad iron.

Extending transversely between and 105 through the front edge portions of the side flanges 10 is a rest pin 12, located intermediately between the top of the main ironing board 1 and the bottom of the rest block 9. This rest pin 12 divides the space 110 between the main ironing board 1 and the rest block 9 into upper and lower tapered

pockets 13, into either one of which may be inserted either one of the tapered end portions of the auxiliary ironing board 2. To secure the auxiliary ironing board 2 in an operative position, above and parallel with the main ironing board 1, one end thereof is inserted into the upper pocket 13, as indicated by full lines in the drawings. When the main ironing board 1 is not in use, the same may be stored compactly by folding the legs 3 and 4 into engagement with the main ironing board 1, as previously described, and by inserting one of the tapered ends of the auxiliary ironing board 2 into the lower pocket 13, as indicated by dotted lines in Fig. 1. In this position of the auxiliary ironing board 2, the same rests in flat engagement with the main ironing board 1.

20 The above described ironing board, while extremely simple and of small cost to manufacture, has, in actual practice, been found highly efficient for the purpose had in view.

What I claim is:

- 25 1. The combination with a table top, of an ironing board, and legs on said ironing board having notched lower ends engageable with the opposite edges of said table top, one of said legs being adjustable and set oblique.
- 30 2. The combination with a table top, of an ironing board, and inwardly projecting oblique legs secured to said ironing board and having, at their lower ends, gripping surfaces arranged to engage opposite edges of said table top.

3. The combination with a table top, of an ironing board, and inwardly projecting oblique legs secured to said ironing board and having, at their lower ends, gripping surfaces arranged to engage opposite edges of said table top, one of said legs being adjustable.

4. The combination with a table top, of an ironing board, and inwardly projecting oblique legs secured to said ironing board and having, at their lower ends, gripping surfaces arranged to engage opposite edges of said table top, one of said legs being connected to said ironing board by a hinged joint.

5. The combination with a table top, of an ironing board, a pair of laterally spaced legs hinged to one end of said ironing board and arranged to be folded thereon into inoperative positions transversely of said ironing board, and a third leg hinged to the other end of said ironing board and arranged to be folded thereon into an inoperative position, longitudinally of said ironing board, said legs, when in operative positions, arranged to project obliquely inward and having notched lower ends, the notches of the said legs arranged to engage opposite edges of said table top.

In testimony whereof I affix my signature in presence of two witnesses.

CHARLES DANIELSON.

Witnesses:

PHILIP E. JOHNSON,
A. CLAIR TOMPKINS.
